[57] CLAIM

The ornamental design of a kiln frame, substantially as
shown.

DESCRIPTION

FIG. 1 shows a perspective view of my ornamental
design for a kiln frame with the door thereof in the open
position;

FIG. 2 shows a top plan view of my design for a kiln
frame;

FIG. 3 shows a front elevation view of my design for a
kiln frame;

FIG. 4 shows a side elevation view of my kiln frame
looking from the left side of the Figures; and,

FIG. 5 shows a sectional view of my kiln frame through
lines 5—5 of FIG. 1.
